LIQUID COOLING SYSTEM

John M. Bruce, New York, N. Y.

Application November 16, 1937, Serial No. 174,761

17 Claims. (Cl. 62—141)

This invention relates to a liquid cooling system and, more particularly, to a method and apparatus for cooling and dispensing brew from the brewers' barrels or containers.

5 In accordance with this invention one or more brewers' barrels are positioned within an insulated cabinet which may be positioned directly under the bar or in a room or space below the barroom. A circulating refrigerant is pumped 10 through cooling coils positioned in the bottom of the cabinet, the refrigerant being supplied by suitable refrigerating mechanism which may be positioned outside the cabinet. The bottom of the cabinet is constructed to provide a leakproof 15 receptacle which contains the cooling liquid in which the cooling coils are immersed. A cooling liquid pump is provided for each brewers' barrel positioned within the cabinet, each pump being driven by an individual motor. A spray head or 20 spray hoop is positioned adjacent the top of each barrel and is provided with suitable spray nozzles or apertures for projecting a spray of cooling liquid over the side walls of the barrel. The cooling liquid may comprise water containing a suitable 25 refrigerant, such as ethylene glycol, so that the temperature of the cooling liquid may be brought down below the freezing temperature of water to a point as low as 10° F.

A dispensing conduit extends from the bottom 30 of each barrel upwardly to a tap positioned adjacent the bar table. Each dispensing conduit is detachably connected to the barrel through a suitable valve connection, which can be detached from the barrel at any time and seal the barrel 35 so as to prevent the outflow of brew therefrom. Thus, the dispensing apparatus can be removed from the barrels as desired for sterilization and cleaning.

Electrical control means are provided for controlling the temperature of the brew flowing 40 through the dispensing conduit and also to control the temperature of the cooling liquid or the atmosphere within the insulated cabinet. A thermal unit, preferably associated with the valve 45 connection which connects the dispensing conduit to the barrel, operates to close a switch in the pump motor circuit connected thereto when the temperature of the brew flowing through the valve connection and into the dispensing conduit 50 rises above a predetermined dispensing temperature, thus throwing the motor into operation, which in turn drives the pump to pump cooling liquid to the spray head or hoop and spray the cooling liquid over the side walls of the barrel. 55 When the temperature of the brew falls below

the desired dispensing temperature range of the brew, say, 40° F., the thermal unit in the valve connection operates to open the switch in the pump motor circuit to halt the motor and terminate further spraying action of the spray over the 5 barrel walls. Thus, the spraying of the barrel walls may be carried on intermittently and only when further cooling of the brew flowing through the dispensing conduit is desired.

Electric control means is also provided for controlling the operation of the compressor motor which supplies cooling refrigerant to the coils through an expansion valve. The electric control means may comprise a thermal control unit positioned in contact with the cooling liquid at the 10 bottom of the cabinet or otherwise positioned in the cabinet. When the cooling liquid held in the pool at the bottom of the cabinet rises above a predetermined temperature range, the thermal unit operates to throw a switch in the motor 15 circuit which operates the refrigerant compressor motor. The compressor, when operating, causes a flow of liquid refrigerant to flow through an expansion valve and through the cooling coils at the bottom of the cabinet and return through a 20 suitable conduit to the compressor in the form of a gas. A refrigerant found to be satisfactory is methyl chloride (CH₃Cl), which refrigerant has no detrimental effect on the conduits through 25 which it flows and which has a high heat-absorption efficiency. The compressor motor may also be electrically-connected and controlled by a thermal element attached to the gas return line feeding the returning gases to the compressor, which 30 thermal element is positioned within the insulated 35 cabinet and may be made operative by the predetermined temperature of the returning gas. When the returning gas reaches a point above a predetermined temperature, this thermal unit 40 will also operate to throw the compressor motor into operation, so as to further cool the cooling liquid and the atmosphere surrounding the barrels in the insulating cabinet.

A pan or catch basin positioned below the barrels receives the spray liquid dropping from the 45 sides of the barrel. This catch pan is positioned at an angle so as to cause the cooling liquid collected therein to flow to one end of the cabinet and through a suitable fine mesh screen which 50 collects any foreign matter which may have dropped into the pan. The cooling liquid drops onto the cooling coils at one end of the cabinet and then flows over the series of cooling coils to the other end of the cabinet, at which end the pumps are statined for pumping the cooling liq- 55

uid back through the spray devices. As thus arranged, it will be noted that the cooling liquid dripping from any of the barrels positioned within the cabinet must flow over and into contact

5 with the full length of the cooling coils at the bottom of the cabinet, thus insuring complete and uniform cooling of the cooling liquid before it is again circulated through the spray devices.

It is thus seen that the temperature of the brew

10 flowing from each individual barrel is independently controlled, providing an efficient and economical brew temperature control mechanism, which operates only when the brew flowing through the dispensing conduit rises above a pre-

15 determined temperature. In like manner, the compressor motor and the refrigerating system only operate when further cooling of the cooling liquid in the cabinet is desired and when the temperature of the cooling liquid in the cabinet rises

20 above a predetermined cooling temperature. The cooling apparatus as thus provided is substantially foolproof in operation and, since the spray heads leading to each individual barrel are individually operated, when cooling of brew in that

25 particular barrel is required, high operating efficiency can be obtained, and repairs or adjustments can be easily and quickly made, should this be desired, due to the fact that all parts are easily and quickly accessible and trouble in the system

30 can be quickly located and corrected. Furthermore, the thermal unit positioned in the brew outflow valve leading from the barrel to the dispensing conduit can be operated at extremely low voltages, so that no danger of shock to the operator or bar attendant can result should the electric control mechanism get out of order. A highly

35 efficient dispensing and cooling system permitting accurate cooling and temperature control of the brew flowing from the brewers' barrel, is thus provided.

40 An object of the invention is to provide an improved cooling system whereby the brew flowing from the brewers' barrels or containers may be accurately controlled and regulated, permitting

45 the drafting of brew from such barrels or containers in the most healthful and palatable condition.

Another object of this invention is to provide an improved brew-dispensing and cooling apparatus assembled in a compact unit, occupying a minimum of space on the brew-dispensing premises, which can be constructed at relatively low

50 cost compared with apparatus heretofore provided, which can be maintained with a minimum of cost and attention, which can be quickly and easily adjusted to suit individual requirements, and which assures dispensing of the brew directly from the brewers' barrel or container in the most

55 healthful and palatable condition.

60 Another object of this invention is to provide a method and apparatus for spraying a cooling liquid projected over a brewers' barrel within a refrigerated cabinet so that cooling of the brew within the barrel will automatically proceed until

65 the desired potable temperature of the brew within the barrel has been obtained, and thereafter which will automatically continue in operation or be thrown out of operation within the maxima and minima limits of a prescribed temperature

70 range.

65 An object of this invention is to provide method and means for cooling a cooling liquid projected over the brewers' barrels in a refrigerated cabinet so that uniform and rapid cooling of the cooling

75 liquid is obtained.

Another object of this invention is to provide automatic means for controlling the brew within the brewers' barrels within the desired potable temperature range.

Still another object of this invention is to provide an improved method and apparatus for dispensing and cooling brew and maintaining the brew within the most palatable temperature range efficiently and economically and with a minimum of attention.

10 Another object of this invention is to provide an improved method for dispensing and cooling brew directly from the brewers' barrel efficiently, economically and expeditiously and in the most healthful, zestful and inviting condition, irrespec- 15 tive of customer demand.

Other objects of this invention will become apparent as the disclosure proceeds.

Various other features and advantages of the invention will be apparent from the following 20 particular description and from an inspection of the accompanying drawings.

Although the novel features which are believed to be characteristic of this invention will be particularly pointed out in the claims appended here- 25 to, the invention itself, as to its objects and advantages, and the manner in which it may be carried out, may be better understood by referring to the following description taken in connection with the accompanying drawings forming a part thereof, 30 in which

Fig. 1 is a rear elevational view of my improved brew cooling and dispensing apparatus as it appears when standing behind the bar, certain parts being broken away to illustrate certain structural 35 features thereof;

Fig. 2 is a horizontal cross-sectional view of my improved brew cooling and dispensing apparatus, this view being taken along line 2—2 of Fig. 1;

Fig. 3 is a transverse vertical cross-sectional 40 view through the brew cooling and dispensing apparatus, this view being taken along line 3—3 of Fig. 1;

Fig. 4 is an end view of the brew cooling and dispensing apparatus, certain parts being broken 45 away to more clearly illustrate certain structural features thereof, this view being taken along line 4—4 of Fig. 1;

Fig. 5 is a diagrammatic view of a wiring dia- 50 gram and associated control mechanism for controlling the temperature of the brew ejected from each individual brewers' barrel;

Fig. 6 is a perspective view of the refrigerating mechanism operatively connected to the cooling coils positioned at the bottom of the insulating cabinet, this view also showing associated therewith the wiring diagram and associated control mechanism for controlling the flow of the refrigerant through the cooling coil;

Fig. 7 is a perspective view of the cooling liquid 60 spray device associated with a brewers' barrel including a driven pump and conduit connection thereto, this view also showing associated therewith the wiring diagram and associated control mechanism for controlling the flow of cooling 65 liquid through the spray head;

Fig. 8 is an enlarged fragmentary cross-sec- 70 tional view showing a portion of the brewers' barrel having a draft tube and draft tube connection associated therewith, the draft tube connection being provided with a temperature control switch, this view being taken on line 8—8 of Fig. 7; and

Fig. 9 is an enlarged fragmentary cross-sec- 75 tional view showing the temperature control

switch as it appears when separately attached to the barrel unconnected with the draft tube connection.

Similar reference characters refer to similar parts throughout the several views of the drawings and the specification.

Referring more particularly to Figs. 1, 2 and 3, my improved brew dispensing system comprises an insulated refrigerated cabinet within 10 which the brewers' beverage transportation barrels are contained. The cabinet may be positioned either directly below the bar or in a room or chamber below the barroom floor. The refrigerating cabinet may be of any suitable size or 15 form to conveniently house the required number of brewers' beverage barrels B, I having illustrated, by way of example only, in Figs. 1 and 2 a cabinet of a size to conveniently contain three brewers' barrels identified as B1, B2 and B3. 20 The cabinet here shown comprises a front wall 1, a rear wall 2, a bottom wall 3, a top wall 4, and end walls 5 and 6, all of which are suitably insulated and reenforced to provide an effectively insulated sturdy construction. More particularly, 25 each of the surrounding walls may comprise an outer sheeting 7 spaced from an inner sheeting 8, preferably of metal, between which is positioned an insulating material 9. The cabinet is provided with suitable door openings 10 for each 30 barrel in the front wall 1 thereof for the convenient insertion and removal of the barrels, a door opening being provided for each barrel to be placed in the cabinet. The door opening is closed by means of a suitable insulated door 11 having a 35 sealing flange 12 which prevents the escape of the cold atmosphere within the cabinet. The cabinet shown in Figs. 1, 2 and 3 may be positioned directly under the bar table with the back wall 2 of the cabinet positioned adjacent the front 40 wall of the bar. It will be appreciated, however, that the refrigerating cabinet can be positioned directly under the bar floor, which is often desirable in the larger brew dispensing establishments.

The brew barrels B1, B2 and B3, as shown in 45 Figs. 1, 2 and 3, are preferably spaced a convenient distance above the bottom wall 3 of the cabinet, the brew barrels being supported upon individual racks which may be formed of metal and which may rest upon the bottom wall 3 50 of the cabinet. Each of the barrel supporting racks may comprise an inclined table portion 15 with a front supporting flange 16 and a rear supporting flange 17 formed integral therewith. The table portion 15 is provided with openings 18 to 55 permit the cooling liquid dripping from the barrel to pass through the table portion and into a drip pan positioned therebelow. The front supporting flange 16 near the door opening is of less height than the rear supporting flange 17 so that 60 the brew barrels are each supported on the table portion 15 in an upright slightly inclined position within the cabinet, the barrels being inclined toward the door openings 10 and the dispensing taps.

65 A drip pan extends substantially the full length and width of the cabinet and is positioned below the barrel supporting racks. The drip pan may be formed from sheet metal comprising a bottom wall 20 slightly inclined toward one end of 70 the cabinet, which bottom wall is closed by surrounding side walls 21. The drip pan is designed to collect a cooling liquid w which is sprayed over the side walls of the barrel and conduct the cooling liquid toward one end of the cabinet, as illustrated more particularly in Fig. 1. A screen 22

of fine wire mesh is provided at the lower end of the drip pan through which the cooling liquid flowing along the drip pan may escape. The screen also operated to segregate and screen out any waste material which may have entered into 5 the cabinet. The drip pan and associated screen 22 may be held in raised position across the bottom wall 2 of the cabinet by suitable supporting legs 23 attached thereto.

A pool of cooling liquid w is stored in the bottom of the cabinet, the bottom wall 3, the front wall 1, the rear wall 2, and the ends walls 5 and 6 being suitably caulked to prevent the escape of the cooling liquid. As shown more particularly in Figs. 1, 2 and 7, the pool of cooling liquid 15 w is circulated at predetermined intervals through an individual spray system for each barrel comprising a pump 25 having an inlet 26 positioned at one end of the cabinet opposite the end of the cabinet where the screen 22 is located. A suitable 20 drain may be provided to permit drainage of the cooling liquid w from the bottom of the cabinet.

As shown more particularly in Figs. 1, 2, 3 and 6, a cooling unit is positioned adjacent the bottom wall 3 of the cabinet and extends substantially the full length thereof to maintain the temperature of the cooling liquid w within which the cooling unit is immersed at the desired temperature. The cooling unit may be of any desired 25 construction. I have shown for purposes of illustration a cooling unit including a serpentine cooling coil 52 immersed in the cooling liquid w, which is supplied with a well known cooling material, such as methyl chloride (CH₃Cl) delivered 30 to the cooling coils 52 under pressure. 35

The refrigerant may be delivered to the cooling coils 52 from a compressor 53 through a supply conduit 54. As the refrigerant passes through the coils it expands into a gas which extracts heat from the surrounding cooling liquid w. The compressor 53 is driven by a suitable driving motor 55 operatively connected to the compressor 53 by means of power transmission mechanism which may be contained within and protected by the 40 box enclosure 56, the mechanism in the box enclosure 56 being connected to the motor 55 by means of suitable drive mechanism. A condenser 57 is provided within which the refrigerant is condensed from its compressed gaseous form to a 45 liquid state. The compressor 53 receives the expanded gas from the coil 52 through a lead pipe 58, which gas passes thence into the compressor 53 where it is compressed. The compressed gas passes from the compressor 53 through a lead 50 pipe 59 into the top of the condenser 57.

The condenser 57 may be of any desired form and may comprise a plurality of serpentine coils 60 provided with cooling fins. A fan 61 driven by the motor 55 blows a stream of air onto the fins 60 to cool the same and extract the heat from the compressed gas, causing the gas to liquidate and drop into a receiver 62. The receptacle 62 is enclosed and connected to the fin coils by means of a suitable conduit connection 63. The liquefied refrigerant passes from the receptacle 62 through the conduit 54 and through an expansion valve 64 located in the cabinet before passing through the lead pipe 65 and thence to the cooling coil 52. The refrigerating machine, as shown 70 in Fig. 6, may be located wherever convenient, but preferably outside of the insulated cabinet. Any suitable refrigerant may be used. Methyl chloride has been found satisfactory due to the 75 fact that it does not have any appreciable cor-

rosive effect on the conduits and is highly efficient for refrigerating purposes.

By referring more particularly to Figs. 1 and 2, it will be noted that the cooling liquid *w* may escape from the drip pan through the screen 22 located at one end thereof only, so that the cooling liquid must flow the entire length of the cabinet and in contact with the cooling coil 52 before the cooling liquid can again enter the screened intake part 26 of the pump 25. A uniform cooling of all of the cooling liquid circulated through the spray system is thus accomplished. Each pump 25 may be of any desired construction, preferably of such construction as to permit the same to operate when immersed in the cooling liquid. It will be noted by referring to Figs. 1, 2 and 7, that each pump is shown operatively connected to an outwardly extending drive shaft extending through a leak-proof gasket embedded in the end wall 5 of the cabinet. A driving motor 28 is connected to each pump drive shaft 27 at a point exterior to the cabinet, the motors 28 being supported by means of a suitable bracket 29 positioned within a motor housing 30. Each motor 28 is operatively connected to its pump 25 by a drive belt 31 trained over the motor pulley 32 and pump pulley 33. As thus constructed, the motor 28 cannot come into contact with the cooling liquid *w*, which might otherwise have a deteriorating effect on the motor, or otherwise adversely affect satisfactory operation thereof.

Each pump 25 is provided with an outlet port 35 connected to a supply conduit which has a portion 36, which rises vertically toward the upper end of the cabinet. If desired, the vertical portion 36 of the supply conduit may be positioned within the insulated end wall 5, so as not to interfere with the free insertion of the brewers' barrel B3 positioned adjacent the end wall 5. The conduit portion 36 is connected to a horizontally extending conduit portion 38 positioned adjacent the top wall 4 of the cabinet, which conduit portion 38 may be supported by means of suitable brackets 39 fixed to the rear wall 2 of the cabinet. Each horizontal conduit portion 38 is tapped to supply the cooling liquid to a spray device or spray hoop 40 positioned adjacent the upper end of each of the brewers' barrels, the spray hoops 40 having suitable spray apertures 41 in the lower face thereof, which openings serve as nozzles to project a downpour of the cooling liquid *w* against the sides of the barrel. The cooling liquid trickles down over the body of the barrel and drips from the bottom of the barrel back into the pool of cooling liquid at the bottom of the cabinet. Thus a film of cooling liquid substantially completely encases the barrel. The conduit portion 38 is connected to the spray hoop 40 by a flexible conduit connection 42 through a T-shaped coupling 43 shown more particularly in Fig. 7. Thus it will be noted that each barrel is individually equipped with a separate spray hoop 40, pump 25, driving motor 28 and individual connections between the pump and spray hoop. As shown more particularly in Figs. 2 and 3 of the drawings each hoop 40 may be provided with a supporting band or bar 40a secured thereto, which band is adapted to rest on the upper end of the barrel to support the hoop in proper spray position. The band 40a also provides a convenient means by which the hoop may be suspended in the cabinet by a bracket 40b when the barrel is removed from the cabinet. The bracket 40b may be attached to the upper wall 4 of the cabinet as shown in Figs. 1 and 2.

Referring more particularly to Figs. 1, 3, 7 and 8, the brew is tapped from the bottom of each barrel and is conducted through a substantially vertically extending draft tube 45 to a dispensing faucet 46 conveniently positioned adjacent the bar table. The dispensing apparatus is detachably connected to the barrel and is so constructed that it can be removed at any time for cleaning and sterilization without appreciable loss of brew and substantially without inconvenience or annoyance to the retail merchant. The dispensing apparatus includes a plug device 47 having a shut-off valve associated therewith, which forms a permanent part of the barrel. A substantially straight draft conduit 45 is detachably connected to an elbow connection 48 which is in turn detachably connected to the plug 47 permanently associated with the barrel.

The plug 47 extends through the side wall 49 of the barrel and is preferably positioned adjacent the bottom wall 50 thereof, as shown in Fig. 8, so that the last drop of brew can be removed from the barrel. The plug connection comprises generally a tubular collar member 66 which tightly fits within a corresponding opening cut in the barrel wall 49. The tubular collar has an end wall 67 on the inner end thereof, which end wall is provided with one or more brew discharge openings 68. A rotatable closure member 69 seats against the end wall 67 and is rotatably mounted thereon by means of a suitable pivot pin or bolt 70. The inner end of the pivot pin or bolt 70 is provided with a head 71 having a generally square contour so that the head 71 can be manipulated by a suitable instrument to rotate the closure member 69. The inner end of the stud bolt 70 is threaded to receive a suitable nut 72. The closure member 69 is provided with a wing portion for each of the openings 68. By turning the square head 71, the wing portions may be manipulated so as to close and open the discharge ports 68 provided in the end wall 67 of the sleeve member 66. The wing portions may be held in closed leakproof, valve-seating engagement over the discharge ports 68 by tightening up on the nut 72, as will be evident by those skilled in the art.

If desired, the wing portions may be provided with a gasket 73 to provide a tight seal, which gasket casing is formed of metal or other material which has no deleterious effect on the brew. It is understood that when the barrels are not in use or when filled with brew during transportation, the wing closures are necessarily arranged in port-closing position and are swung into port-opening position only when the dispensing apparatus now to be described is attached thereto.

The dispensing apparatus comprises a separate elbow connection 48, as more particularly illustrated in Fig. 8. The elbow connection comprises a substantially straight tube portion 75 and a riser portion 76, which is detachably connected to the lower end of the vertically extending draft conduit 45 by means of a coupling 77 provided with handle portions 79 to facilitate manipulation thereof. The end of the tube portion 75 is provided with a nipple 80 which extends into the collar 47. The end of the nipple is provided with a square opening or socket 81 shaped to receive the square head 71. The tube portion 75 is also provided with a collar portion 82 which seats against a shoulder 83 extending inwardly from the collar member 47. The collar portion 82 is provided with a gasket member 84, preferably formed of metal, which seats against the shoulder portion 75.

83 and provides a leakproof fit therebetween. The elbow connection is fixedly retained to the plug device 47 by means of a pair of wing elements 85 extending laterally from the tube portion 75. The wing elements 85 are insertable through corresponding openings provided in the collar member 86. By turning the elbow connection 48, the wing elements 85 may be inserted through the bayonet slots provided in collar member 86, and by again turning the elbow connection 48, the wing elements 85 can be swung into locking engagement with the inwardly extending lips positioned between the bayonet slots to provide a leakproof connection.

15 The relatively straight conduit portion 48 is provided with a brew-containing passage e sufficiently large to permit the insertion therein of a thermometer or thermo member 90, which preferably extends centrally of the brew passage e so as to permit the brew to flow around the same in passing into the riser portion 76 of the elbow connection. The thermo member 90 is provided with a suitable threaded neck portion 91 which may be screwed into a boss portion 92, a suitable 20 gasket 93 being provided to prevent leakage of the brew out through the boss portion 92. The neck portion 91 of the thermal unit 90 may also be provided with a nut 94 to further lock the thermal unit in position and prevent leakage of the 25 brew. The neck portion 91 of the thermal unit 90 is provided with an electrical switch element, well known in the art, which element is connected to electrical terminals 95 and 96. The switch element, contained in the neck portion 91, is so 30 constructed that when the brew in the conduit portion 48 rises above a predetermined temperature, the switch will be closed by the action of the thermal unit, permitting electrical current to flow through the terminal wire 95 and through 35 the motor switch 97 housed within the switch box 98.

The thermal unit is so adjusted as to close the switch when the temperature of the brew in the conduit portion 48 rises above the desired potable 40 temperature of the brew, which is approximately 42° F. The thermal unit 90 may comprise either a mercury controlled switch, well known in the art, which is controlled by the expansion of the mercury in the thermal unit, or, preferably, 45 comprises a metallic member which is affected by changes in temperature and controls the switch mechanism. Both types of thermal units above described are generally known in the art, making unnecessary a detailed description of the construction and operation thereof.

50 As shown in Fig. 9, the thermal control switch might also be mounted in a bung 200 to support the thermal unit 90 which projects into the barrel, although it is preferable to mount it in the elbow connection 48 of the dispensing mechanism so that it forms a part thereof, the brew draft mechanism being detachable to permit cleaning 55 and sterilization thereof.

Referring more particularly to Figs. 5 and 7, 60 current is supplied to each of the individual motors 28 through power lines 100 and 101. Current flows from the power line 101 through the connecting wires 108 and 109 to the motor 28 and thence flows through the motor wire 99 65 to a terminal point 105 in the switch box. The switch 97 comprises more particularly a solenoid 102 which operates a magnet 103 having a terminal 104. When the solenoid 102 is energized, the terminal 104 is moved into contact with 70 75 terminal points 105 and 106, thus closing the

motor circuit and permitting current to flow through the lead wire 99 through the terminal point 105 through the terminal connection 104 through the terminal point 106 and finally through the lead wire 110 to the power wire 100. 5 It will be noted, however, that the solenoid 102 is energized by the thermo switch 90. The terminal wire 95 from the thermo switch 90 is connected to the solenoid 102, and lead wire 111 from the solenoid is connected to the lead wire 10 110 connected to the power wire 100. Terminal wire 96 leading from the thermal unit 90 is preferably connected to a suitable stepdown transformer or resistance 107 which is connected to the lead wire 112 and to the lead wire 108 connected to the power wire 101. 15

Assuming that the brew flowing into the passage e of the elbow portion 48 rises above a potable temperature of, say, 42° F., it will be noted that the thermal switch 90 will close 20 solenoid circuit, which permits a flow of electrical energy from the power line 101 through the lead wires 108 and 112, through the resistance 107 to the terminal wire 96, through the thermo switch 90, through the terminal wire 95, through 25 the solenoid 102, through the lead wires 111, 110 and back to the power wire 100, completing an electrical circuit which operates to energize the solenoid 102. Upon energization of the solenoid 30 102 the terminal connection 104 moves into contact with the terminal points 105 and 106 so as to close the motor circuit. Electrical current will then flow from the power wire through the lead wires 108 and 109, through the motor 28, through the lead wire 99, through the terminal point 105 and then through the terminal connection 104, through the terminal point 106, through the lead wire 110 to the power wire 100. The motor will continue to operate until the 35 thermal switch 90 breaks the circuit so as to de- 40 energize the solenoid 102, permitting the contact connection 104 to move out of electrical contact with the contact points 105 and 106, thus breaking the motor circuit and halting the motor.

It will be understood that there is an independent motor 28 and electrical circuit connection for each spray hoop 40, so that only those barrels are sprayed with cooling liquid whose brew contents have risen above the desired predetermined temperature. Since each motor and 50 motor circuit, including switch 97 and thermal switch 90 may be of similar construction and similarly connected to the power wires 101 and 100, they need not here be further described.

Referring more particularly to Fig. 6, the motor 55 which operates the compressor is also thermostatically controlled by a wiring connection which may be similar to that described and illustrated in Fig. 7. A thermal switch 120, of suitable type, may be connected to the refrigerant return pipe 60 58, so as to be thrown into and out of operation by the temperature of the returning refrigerant gas. In other words, when the refrigerant gas returning through the conduit 58 rises above a predetermined temperature, the thermal switch 65 120 is closed so as to throw the motor switch in the switch box 121 to operate the motor and drive the liquid refrigerant through the liquid refrigerant supply pipe 54, the connection 65 and the coils 52. The motor switch contained in the 70 switch box 121 may comprise a solenoid switch similar to the switch 97 which throws the pump motor 28 into and out of operation.

When the thermal switch 120 is closed, current 75 will flow from the power line 101 through the

lead wire 122, through the motor wire 123, through the compressor motor 55 and back through the motor lead wire 124 into the switch box 121 to a terminal point 125 therein. When 5 the solenoid 126 is energized, as will be herein-after explained, the core 127 thereof moves the terminal connection 128 into contact with terminal points 125 and 129, terminal point 129 being connected to lead wire 130 to the power 10 wire 100.

When the thermal switch 120 is closed, the solenoid 126 is energized by current which flows from the power wire 101 through lead wire 122, through lead wire 131 and through the thermal 15 unit 120. From the thermal unit 120, the current flows through the lead wire 132, through the solenoid 126, through the lead wires 133 and 130 and back to the power wire 100. Thus, it is seen that upon closing of the thermal switch 120, the 20 solenoid 126 will be energized so as to move the terminal connection 128 into electrical contact with the contact points 125 and 129 to close the motor circuit and throw the motor 55 into operation so as to circulate the refrigerant through 25 the cooling coil 52.

It will be understood that, if desired, the thermal unit 120 may be positioned in the cooling liquid *w* so that the compressor motor 55 will be thrown into and out of operation by the 30 changes in temperature of the cooling liquid *w* contained in the pool at the bottom of the cabinet. It will also be noted that the electrical connections and switches for the compressor motor 55 are substantially the same as the electrical 35 connections and switches used in connection with the individual pump motors 28. The switches 97 and 126 may all be contained within a single switch box 98 mounted on the end wall 5 of the cabinet.

40 The thermal units 90 may be encased in suitable insulation so that their operation is not affected either by the temperature of the cooling liquid dripping from the barrel or the spray hoops 40, or by other outside influences, except 45 only the brew temperature in the passage *e* of the elbow connection 48. As shown more particularly in Figs. 7 and 8, the elbow connection 48 may be insulated by means of suitable insulating material 87 which is surrounded and 50 contained within an outer shell or casing comprising two half portions 88 and 89 which can be separated to permit ready removal and detachment of the elbow connection 48 from the sleeve 47. It will also be appreciated that when 55 the elbow connection 48 is sterilized, the thermal unit 90 may be withdrawn therefrom by unscrewing the threaded neck portion 91 thereof from the boss 92.

60 The brew is forced from the brew barrels by means of a suitable gas, such as air or carbon dioxide. The gas is supplied through a supply conduit 140, as shown in Fig. 2, and is conducted to each barrel through a flexible branch conduit 141. A suitable valve 142 may be provided to 65 regulate the flow of the gas through the supply conduit 140 to the respective branch conduits 141. The branch conduits 141 are each connected to the barrel head through a suitable connection 143, which is detachable from the barrel. 70 The gas pressure forced into the barrel should maintain the charged brew drawn from the faucets 46 in equilibrium, so that the brew in the barrel does not become overcharged with carbon dioxide gas and at the same time prevent 75 escape of the desirable carbon dioxide gas with

which the brew is charged when manufactured by the brewer. It has been found that the brew will best retain the most palatable amount of carbon dioxide gas when the pressure of the gas flowing through the branch conduits 141 is in 5 the nature of approximately 12 lbs. per square inch, which equilibrium pressure is maintained in each of the brew barrels during withdrawal of the brew therefrom.

It will now be understood that individual thermal switches and motor switches controlling the operation of individual pump motors is provided. Suitable stepdown transformers may be provided so as to reduce the voltage flowing through the thermal units 90 to a low voltage to 10 eliminate danger of shock to the attendant, so that the operator or bar attendant will not receive an electrical shock by reason of contact with wet surfaces surrounding the cabinet in event any electrical connection should become 15 broken or disarranged. Likewise, the compressor motor 55 is controlled in its operation by a thermal switch either placed in the cooling liquid at the bottom of the cabinet or attached to the return pipe 58 through which the refrigerant 20 gas returns to the compressor.

A substantially foolproof and highly efficient brew cooling system is thus provided, which operates on a minimum of power and requires a minimum of attention. The cooling cabinet and 30 operating mechanism for cooling the brew barrels is relatively simple in construction and is presented in a compact unit which can be manufactured at relatively low cost and quickly installed. The brew dispensing mechanism is 35 adapted to be quickly and easily detached from the brew barrel irrespective of the amount of brew therein so that periodic cleaning and sterilization of the draft mechanism may be efficiently and thoroughly effected. It will be appreciated that various different forms of thermo-electric control devices in general use may be associated with the mechanism and it is understood that the thermal control unit, particularly shown in the drawings and described above, are 40 presented for the purpose of illustration only and not by way of limitation.

While certain novel features of the invention have been disclosed and are pointed out in the annexed claims, it will be understood that various omissions, substitutions and changes may be made by those skilled in the art without departing from the spirit of the invention.

What is claimed is:

1. A brew apparatus for use in a brew dispensary including, an enclosed chamber adapted to accommodate a plurality of brew transportation containers therein, refrigerating coils positioned adjacent the bottom of said chamber, a cooling device operative to circulate a film of the cooling liquid over a substantial part of such container walls to cool the brew therein, means for collecting the cooling liquid which has passed over such containers and conducting the same toward one end of said chamber, and means for 60 conducting said cooling liquid toward the opposite end of said chamber in flowing contact with said refrigerating coils to re-cool the same.

2. A brew apparatus for use in a brew dispensary including, a chamber adapted to accommodate a heat-insulated brewers' beverage container, a spray device for projecting a cooling liquid over the exterior of such container, a pump, a supply conduit connecting said pump and spray device, a pan positioned to receive and 75

collect the cooling liquid which has passed over such container, refrigerating means, and means for conducting the cooling liquid collected in said pan into cooling contact with said refrigerating means before said cooling liquid is again returned to the pump.

3. A brew apparatus for use in a brew dispensary including a chamber adapted to accommodate a heat insulated brew container, refrigerating means within said chamber, spray means for forming a moving film of cooling fluid over a substantial exterior area of such container to cool the brew therein, a pan positioned above said refrigerating means to receive and collect the cooling fluid which has passed over such container, and means for conducting said cooling fluid into cooling contact with said refrigerating means.

4. A brew apparatus for use in a brew dispensary including, a heat-insulated cabinet adapted to accommodate a plurality of brewers' beverage barrels therein, refrigerating means within said cabinet extending substantially the length thereof, means for spraying a cooling liquid over the exterior of such brewers' beverage barrels positioned in the cabinet to cool the brew therein, a pan supported in an inclined position for collecting and conducting the cooling liquid which has passed over such brewers' barrels toward one end of the cabinet, pumps for supplying cooling liquid to said spray means, and means for supplying said pumps with cooling liquid drawn from the other end of the cabinet whereby the cooling liquid is required to flow into cooling contact with substantially the entire length of said cooling means before it enters said pumps.

5. A brew installation including, an insulated cabinet adapted to accommodate a plurality of brewers' beverage barrels therein, a receptacle for cooling liquid, means for supporting said barrels in spaced relationship from said receptacle, a drip pan positioned above said liquid receptacle, means for projecting a cooling liquid over one of such barrels, a screen at one end of said pan through which the cooling liquid dripping from the barrel and into said pan may escape from said pan, a pump adjacent one end of said pan opposite which said screen is located, means connected to said pump for supplying cooling liquid to said spray means, and cooling means in said receptacle operative to cool the liquid in said receptacle.

6. A brew apparatus for use in a brew dispensary including, a cabinet adapted to contain a brewers' beverage barrel therein, means for projecting a spray of cooling liquid over said barrel, a pump for supplying cooling liquid to said spray means, thermo-electric control means operative upon predetermined changes in temperature of the brew in or flowing from said barrel, a motor for driving said pump, and an electric circuit electrically connecting said motor to said thermo-electric control means.

7. A brew apparatus for association with a brewers' container in a brew dispensary, a spray head for forming a moving film of cooling liquid over the side walls of a beverage container, a pump, a motor for driving said pump, a conduit connecting said pump and spray head, a thermo-electric switch operative upon predetermined changes in temperature of the brew in or flowing from said container, a motor switch for throwing said motor into and out of operation, and an electric circuit electrically connecting said thermo-electric switch, motor switch and motor

whereby to throw said motor into and out of operation in accordance with predetermined temperature changes of the brew in the container.

8. A brew apparatus for use in a brew dispensary including, an insulated cabinet adapted to accommodate a brewers' beverage barrel therein, a cooling liquid receptacle in said cabinet, a cooling coil positioned in said receptacle operative to effect heat exchange with the cooling liquid in said receptacle, a refrigerant compressor, a motor for driving said compressor, conduits connecting said compressor to said cooling coil, and a thermo-electric switch operative upon predetermined changes in temperature of said cooling liquid to throw said compressor motor into and out of operation.

9. A brew apparatus for use in a brew dispensary including, a cabinet adapted to accommodate a brew container therein, a cooling coil in said cabinet, a refrigerant compressor, a motor for driving said compressor, conduits connecting said compressor to said cooling coil, a motor switch, a thermo-electric switch operative upon predetermined changes in temperature of the atmosphere in said cabinet, and an electric circuit connecting said thermo-electric switch, motor switch and motor whereby said motor is thrown into and out of operation upon predetermined changes in temperature of the atmosphere in said cabinet.

10. A brew apparatus for use in a brew dispensary including, a heat insulated cabinet adapted to accommodate a plurality of brewers' beverage barrels therein, a spray device for each barrel accommodated within the cabinet, each spray being operative to project a cooling liquid over the barrel associated therewith, a pump for each of said spray devices, a conduit connected to each pump and one of said spray devices for supplying cooling liquid thereto, means for driving each of said pumps, and means for individually controlling said pump-driving means so as to throw each pump into and out of operation upon predetermined changes in temperature of the brew in or flowing from each corresponding barrel.

11. A brew apparatus for use in a brew dispensary including, an insulated cabinet adapted to accommodate a plurality of brewers' beverage barrels therein, a spray device for each barrel accommodated within the cabinet to project a spray of cooling liquid in cooling contact therewith, individual means for supplying cooling liquid to each of said spray devices, means for operating said cooling liquid supplying means upon predetermined changes in temperature of the brew in the individual barrels, a cooling coil in said cabinet, means for supplying refrigerant to said cooling coil, and means for controlling the flow of refrigerant through said cooling coil upon predetermined changes in temperature occurring within said cabinet.

12. Apparatus for use in a brew dispensary including an insulated cabinet adapted to accommodate a removable brew container, a spray ring, means for supporting the spray ring in surrounding relation to one end of such container, a receptacle for cooling liquid, means for cooling the liquid in said receptacle, a cooling liquid supply line in said cabinet, a flexible conduit connecting said supply line to said spray ring whereby said spray ring may be moved into various positions of adjustment, and a pump operative to supply cooling liquid from said receptacle

to said spray ring through said supply line and flexible conduit.

13. Apparatus for cooling brew in a brewers' transportation barrel including a tubular spray ring, means connected to said ring adapted to engage such a brewers' transportation barrel to removably support said ring in surrounding relation over the end of the barrel, and a flexible cooling liquid supply conduit connected to said spray ring.

14. Brew cooling apparatus for use in a brew dispensary including, shower means for projecting cooling liquid over a container for brew, cooling liquid supply means including a pump and conduit for supplying cooling liquid to said shower means, a driving motor operatively connected to said pump, a thermo-electric switch operative upon predetermined changes in temperature of the brew in said container, and an electric circuit electrically connecting said motor to said thermo-electric switch.

15. Brew cooling apparatus for use in a brew dispensary including, means for projecting a spray of cooling liquid over a brew container for the purpose of cooling the brew contents thereof, a pump for supplying cooling liquid to said spray means, thermo-electric control means adapted for association with a brew conduit leading from said container and operative upon predetermined temperature changes of the brew residing in or flowing through said conduit, a motor for driving said pump, and an electric circuit electrically connecting said motor to said thermo-electric control means.

16. Brew cooling apparatus for use in a brew dispensary including, a cabinet adapted to accommodate a brewers' beverage container therein, a thermo-electric switch device including a thermal element adapted to extend into the

beverage within or flowing from such brewers' beverage container and operative upon predetermined temperature changes of the beverage residing in or flowing from said brewers' container, means for cooling the beverage in said container, means for supplying a cooling liquid to said cooling means, means operatively connecting said thermo-electric switch device to said cooling liquid supply means for controlling the flow of cooling liquid in said cooling means upon predetermined changes in temperature of the beverage residing in or flowing from said brewers' container, and a casing of insulation surrounding said thermal element to protect the same from temperature changes other than the changes in temperature of the beverage residing in or flowing from said brewers' container.

17. Apparatus for cooling brew including, a cabinet, said cabinet having a cooling chamber provided with insulated walls adapted to accommodate a brew container therein, cooling coils in said cabinet, a refrigerant compressor positioned exterior to the insulated walls of said cooling chamber, a conduit extending from said compressor through an insulated wall of said chamber and connected to said coil for supplying a cooling refrigerant thereto, a motor operatively connected to said compressor for driving the same, a thermo-electric switch having a thermal element in said insulated chamber, a motor switch, and an electric circuit electrically connecting said thermo-electric switch, motor switch and motor, said thermo-electric switch being operative through said motor switch to throw said motor into and out of operation in accordance with predetermined temperature changes occurring in said insulated chamber.

JOHN M. BRUCE.
